UNITED STATES PATENT OFFICE.

CHARLES H. CROWELL, OF WHITE PLAINS, NEW YORK.

CORRUGATED-BOARD CONTAINER AND BLANK THEREFOR.

Application filed December 11, 1923. Serial No. 679,880.

This application is a partial continuation of my copending cases Serial No. 494,073, filed August 22, 1921, and Serial No. 569,854, filed June 19, 1922, and contains subject matter taken therefrom.

This invention relates especially to shipping containers made of corrugated paper board in which the body of the container may advantageously comprise a three or 10 four sided blank having transverse creases between the sides and preferably having its edges rabbeted or stepped so as to form a projecting edge flange which comprises the outer facing or liner sheet of the paper board. This stepped edge may be greatly 15 reinforced by pasting thereon a seam or edge reenforcing tape of gummed cloth or paper which engages the inner facing of the corrugated board and also adhesively engages the 20 cut or rabbeted edge and the projecting edge flange and is folded around the edge of the flange and the tape edge secured to the outer facing, so as to greatly strengthen this projecting flange against splitting in case the 25 cooperating member of the container is forced out against it. The body blank may have secured thereto one or more free sealing flaps or tapes preferably having corner folding notches so that after the cooperating 30 blanks or members of the container are assembled and glued or secured in place, if desired, these sealing flaps may be pasted over the same to securely and strongly hold them in place and tightly close the container. In 35 some cases, however, it is desirable where the blanks are to be shipped long distances before being assembled and used, to originally 40 secure the sealing flaps or tape strips to the edges of the upper and lower covers so as to leave free sealing flaps which may be folded back against or adjacent the cover for shipping purposes. In some cases it is also desirable to adhesively secure single or double 45 gummed reenforcing tape around the edges of the cover blanks before applying the sealing strips thereto so as to strengthen these edges and practically seal the air spaces comprised in the covers.

In the accompanying drawing which 50 shows in a somewhat diagrammatic way sev-

eral illustrative embodiments of the invention—

Fig. 1 is a perspective view of an illustrative container,

Fig. 2 is a plan view of a blank therefor, 55

Fig. 3 is an enlarged sectional detail showing the form of edge joint and sealing members,

Fig. 4 is a similar sectional view where transversely or cross-corrugated paper board 60 is used for the container elements, and

Fig. 5 is a perspective view showing a container in which the sealing tape is attached to the cover.

The body blanks for these containers may 65 be made of ordinary or cross corrugated paper board and of such size and proportion as to suit the particular container desired. As is shown in Figs. 1 and 2, the container may comprise a four-sided straight strip 70 body blank having the transverse folding creases 6 formed therein between the adjacent sides 1, 2, 3, 4 and it is usually desirable to have the corrugations run vertically or transversely of the length of this body blank 75 in cases where single corrugated paper board is used for making the same. As is shown more in detail in Fig. 3, the edge portions of the blank which may be formed with special or heavy facing sheets may advantageously be given a rabbeted or stepped form 80 so as to leave a projecting edge flange 18 comprising the outer facing 16 of the corrugated board to which the usual corrugated spacing member 17 is adhesively secured. These stepped edges of the body 85 blank may be produced in any desired way and may be formed or finished by grinding with coarse emery wheels or the like so as to give smooth and accurate edges. These 90 projecting edge flanges or stepped edges 11, 12 of the body blank may be greatly strengthened and reinforced by adhesively securing thereto flange reenforcing tape such as 15 which may be strong gummed paper 95 or cloth tape such as sixty-pound kraft paper having adherent gum coatings on one or both sides and which may be adhesively secured at 15 to the inner facing and may then extend at 14 across the spacing member 17. 100

This edge flange reenforcing tape may then be secured at 13 to the inner face of the flange 18 and may extend at 19 around its edge and then be adhesively secured at 20 to its outer face and to the adjacent portions of the outer facing as at 21. In this way this edge flange is enclosed and supported and strongly connected to the inner facing sheet of the corrugated board so as to be greatly strengthened against outward pressure exerted by the cover members of the container, for instance, so that splitting off of this projecting flange is thus minimized. Both the upper and lower edges of the body blank may be similarly provided with such tape reinforced stepped edges or projecting flanges and it is, of course, advantageous to have this reenforcing tape applied at the factory where the blanks are shaped and creased where this tape may be attached by experienced operators under standard conditions.

It is, of course, understood that where a straight strip body blank is used as shown in Fig. 2 a connector tape of gummed cloth or paper such as 9 may be secured to the body blank at the factory and adhesively secured to the other end of this body blank as shown in Fig. 1 when the container is made up and used. In some cases it is advantageous to form this connector tape slightly longer than the width of the body blank so that its ends may be folded over the edges of the body blank and adhesively secured to the inner faces of these parts so as to engage and hold together the projecting edge flanges for instance in some cases.

It is advantageous to use separate top and bottom covers with such body blanks and covers may be made of single or double corrugated paper board of the proper size so as to preferably fit within the projecting edge flanges of the body blank as shown in Fig. 3 so that they can be securely held in this position by suitable sealing tape, for instance, which may be originally secured to the body or cover blanks or applied to the joint when the blanks are assembled to form the container. A strong and efficient construction can be secured when the sealing tape is originally applied to the body blank as is shown in Figs. 2 and 3, this sealing tape of heavy gummed paper or cloth being securely attached to the edges of the body blank as at 25 so as to leave projecting edges or free sealing flaps 5 which are preferably more or less separated by corner folding notches such as 10 in the tape. When the container is assembled these sealing flaps may be moistened and folded down on the cover 7, for instance, as shown in Fig. 1 so as to form a strong and substantially tight seal for the container. In some cases it is advantageous to use single or double gummed paper or cloth tape as a cover edge reen-

forcement extending around some or all the edges of the covers, as is shown in Fig. 3, where the tape 23 extends around and practically seals the edge of the cover 7 and greatly strengthens the same in connection with the edges 22, 24 of this reenforcing tape which engage the adjacent faces of the cover. Where double gummed tape is used for this edge reinforcement of the cover it may be moistened so as to have effective securing and sealing action in connection with the adjacent stepped edges and projecting flange of the body blank and the sealing tape which may be used to unite these parts. As is shown in Fig. 4 cross corrugated paper board may be used for both the body and cover blanks, if desired, and may comprise the corrugated spacing members 27, 29 adhesively secured in any suitable way to the facing sheets 26, 28 and 30. Stepped edges may be formed on such a body blank, preferably by removing the sheets as indicated in Fig. 4 so as to leave a projecting flange consisting of or comprising in connection with other of the sheets the outer facing sheet 26 which may be of heavy or special strong paper and this edge flange 18 may be similarly strengthened by being enclosed in the flange reenforcing gummed tape applied and secured to these parts as described in connection with Fig. 3. The cover 7 may then be put in place so as to engage this stepped edge of the body blank and rest upon the portion 31 to which it may be adhesively secured by any suitable means as by additional adhesive applied between these surfaces, if desired, so as to cooperate with the sealing tape applied to the joint as, for instance, by first being adhesively secured to the edges of the body blank so that the free sealing flaps 5 may be forced down over the edges 32 of the cover.

For convenience of shipping these blanks it is often desirable as shown in Fig. 5 to have the sealing strips or flaps originally secured to the covers such as 7 to which they may be pasted or secured in the form of separate strips of gummed tape, for example, so as to leave free edges 25 of these sealing flaps which for shipping purposes may be folded or bent back adjacent the cover so as not to be torn or undesirably bent during shipment. Then when the cover is put in place on the assembled body blank these sealing flaps may be moistened and then folded down over the edges of the body blank as shown at the left of Fig. 5 so as to make a strong and secure union therewith and effectively seal the joint, especially where the cover has been provided with single or preferably double gummed reenforcing tape 22, 23, 24, the exposed faces of which may be moistened where they engage the body blank so as to strongly adhere thereto.

This invention has been described in con-

nection with a number of illustrative embodiments, forms, portions, parts, materials, arrangements and methods of manufacture and use, to the details of which disclosure 5 the invention is not of course to be limited, since

What is claimed as new and what is desired to be secured by Letters Patent is set forth in the appended claims.

- 10 1. The corrugated paper board shipping container comprising a four sided straight strip body blank of corrugated paper board formed with heavy facing sheets and having the corrugations arranged transversely 15 of the length of the blank and having transverse folding creases between the adjacent sides, said blank being formed with stepped edges in which the outer facing of the corrugated board constitutes a projecting edge 20 flange, seam reenforcing tape secured to said stepped edges and adhesively secured to the inner facing of the corrugated board and across the severed edge of the corrugated board and secured to the inner and outer 25 faces of the outer facing sheet adjacent the edge flange to strengthen the same and minimize the splitting off of this flange under outward pressure, and separate top and bottom covers of corrugated paper board 30 having free sealing flaps formed of separate strips of gummed tape having one edge adhesively secured adjacent the corresponding edge of the cover member and folded back against its outer face and adapted to be adhesively secured to the adjacent portions of 35 said body blank.
2. The corrugated paper board shipping container comprising a four sided straight strip body blank of corrugated paper board 40 formed with stepped edges in which the outer facing of the corrugated board constitutes a projecting edge flange, seam reenforcing tape extending around and enclosing said edge flange and adhesively secured

thereto and to the adjacent inner facing sheet to strengthen the edge flange, and 45 separate top and bottom covers of corrugated paper board adapted to be adhesively secured to the adjacent body portions of said body blank. 50

3. The corrugated paper board shipping container comprising a body blank of corrugated paper board formed with stepped edges having seam reenforcing tape extending around and strengthening the stepped edges, and separate covers of corrugated paper board having their edges enclosed by adhesively secured reenforcing tape and having free sealing flaps adhesively secured adjacent the edge of the cover member and 55 adapted to be folded back against its outer face and to be adhesively secured to the adjacent portion of said body blank. 60

4. The multiple side container body blank 65 of corrugated paper board formed with folding creases and with stepped edges and seam reenforcing tape secured to the opposite sides of the facing members of the corrugated board adjacent said stepped edges and locked around the edge of the projecting edge flange to strengthen the same against outward pressure, and cooperating covers of corrugated paper board having edges engaged by adhesively secured reenforcing tape and having sealing flaps adhesively secured adjacent the corresponding edge of the cover and having their free edges folded back adjacent its outer face for shipping 70 and adapted to be adhesively secured to the adjacent portions of said body blank. 75

5. A shipping container having a stepped edge with a projecting edge flange and a seam reinforcing tape secured to the inner face of the container and extending over the step and projecting flange into secured 80 engagement with the outer face of the container. 85

CHARLES H. CROWELL.
